(57) **CLAIM**

The ornamental design for a clip for clip-on sunglasses, substantially as shown and described.

DESCRIPTION

FIG. 1 is a perspective view showing the clip for clip-on sunglasses shown in dot and dash;

FIG. 2 is a perspective view showing the clip of my invention;

FIG. 3 is an elevation view of one side of my invention, the other side being the mirror image thereof;

FIG. 4 is an elevation view of the front of my invention;

FIG. 5 is an elevation view showing the rear of my invention;

FIG. 6 is an elevation view of the top of my invention; and,

FIG. 7 is an elevation view of the bottom of my invention.

The sunglass lenses depicted in dot and dash in FIG. 1 do not form part of the claimed design.
